US00D786914S

(12) **United States Design Patent** (10) **Patent No.:** **US D786,914 S**
Kim et al. (45) **Date of Patent:** **** May 16, 2017**

(54) **DISPLAY SCREEN OR PORTION THEREOF WITH GRAPHICAL USER INTERFACE**

(71) Applicant: **SAMSUNG ELECTRONICS CO., LTD.**, Suwon-si (KR)

(72) Inventors: **Sora Kim**, Seoul (KR); **Cheolhoon Kang**, Seoul (KR)

(73) Assignee: **SAMSUNG ELECTRONICS CO., LTD.**, Gyeonggi-Do (KR)

(**) Term: **15 Years**

(21) Appl. No.: **29/550,265**

(22) Filed: **Dec. 31, 2015**

(30) **Foreign Application Priority Data**

Sep. 7, 2015 (KR) 30-2015-0045307

(51) LOC (10) Cl. **14-04**

(52) U.S. Cl.

USPC **D14/487**

(58) **Field of Classification Search**

USPC D14/485-495; D10/126

CPC H04M 1/2477; G06F 2203/04807

See application file for complete search history.

(57) **CLAIM**

We claim, the ornamental design for a display screen or portion thereof with graphical user interface, as shown and described.

DESCRIPTION

FIG. 1 is a front view of a display screen or portion thereof with graphical user interface showing our new design in a first embodiment;

FIG. 2 is a front view of a display screen or portion thereof with graphical user interface showing our new design in a second embodiment; and,

FIG. 3 is a front view of a display screen or portion thereof with graphical user interface showing our new design in a third embodiment.

(Continued)

The broken line showing of the alphanumeric characters, symbols, and display screen in the figures is for environmental purposes only and forms no part of the claimed design.

1 Claim, 3 Drawing Sheets
